BOX

Joseph G. Huye, New Orleans, La.

Application February 1, 1936, Serial No. 61,999

2 Claims. (Cl. 229—23)

This invention relates to knock-down set-up boxes of the type shown in my Patent No. 2,025,589 granted December 24, 1935, and is an improvement on the invention set forth in said patent.

The present invention has for its primary object to reduce the number of locking tongues and sockets and to so form the box bottom that it may be entirely formed from a single integral piece of pasteboard, thus eliminating the use of separate confining or backing strips, such as strips 7 of my said patent, whereby great economy of manufacture is accomplished while at the same time a stronger box bottom is obtained.

15 In the accompanying drawings:

Figure 1 represents a perspective view of a box embodying my invention;

Figure 2, a top plan view of the box bottom blank in partially finished condition before the 20 panels 4 have been pasted or glued to the panels 2;

Figure 3, a perspective fragmentary view of one corner of the bottom C finished and in an intermediate stage of erection;

25 Figure 4, a perspective view of the bottom C in finished condition fully erected;

Figure 5, a sectional view on line 5—5 of Fig. 7, looking in the direction of the arrows;

Figure 6, a sectional view on the line 6—6 of 30 Fig. 7, looking in the direction of the arrows;

Figure 7, a sectional view on the line 7—7 of Fig. 5, looking in the direction of the arrows, the corner laps 8 and 10 being shown in edge elevation;

35 Figure 8, a plan view of the body blank prior to final pasting;

Figure 9, a top plan view of the body B in finished condition with the top bracing and spreading flanges E' extending straight in continuation, and with the lower bracing and spreading flanges E folded at right-angles inward into operative interengaging position and with the locking tongues F extending laterally and upwardly at an inclination;

40 Figure 10, a plan view of the blank for top A in partially finished condition;

Figure 11, a fragmentary perspective view of a lower corner of the body B;

45 Figure 12, a fragmentary sectional view, broken away, on line 12—12 of Fig. 1, looking in the direction of the arrows; and

Figure 13, a fragmentary sectional view on the line 12—13 of Fig. 1, looking in the direction of the arrows.

50 Referring now in detail to the drawings, A

designates the top; B the body and C the bottom, the top or cover A being removable and replaceable on the upper end of the body B and the bottom C being, in assembled relation, locked to the lower end of the body B so as to be inseparable therefrom without mutilation and without the use of special tools.

The body B may be formed of a suitable cardboard or paste-board blank vertically scored at suitable points with fold lines and provided with 10 an adhesive-coated lap G for pasting it together in the form of a square or other suitable form body provided at its top with preferably integral inwardly folding mitred end spacing and bracing flanges E' and at its lower end with similar 15 flanges E having the same functions, there being provided preferably integral laterally outwardly upwardly inclined locking tongues F, all constructed, arranged and functioning as set forth and described in the patent above referred to. 20

The bottom C will be of such size and shape as to just snugly receive between the inner faces of its lip or flange the lower end of the body B, said lip being of such height as to extend upward along the body B beyond the upper ends of the 25 locking tongues F and being formed with tongue-receiving sockets or openings 9 in the panels 4 and tongue passage openings 9' in the panels 3.

30 Preferably adhesive, as indicated by stippling in Fig. 2, will be applied to the outer faces of the panels 4, which are to be folded inward along a scored line a and pasted to the inner faces of the panels 2 respectively. The inner end flaps or laps 8 cut free from outer end flaps or laps 10 respectively on lines 12 respectively in alignment 35 with the respective fold lines a but extending from the respective end portions of the respective panels 4 fold over inward with the respective panels 4 to lie against the inner faces of the respective end flaps or laps 10 respectively 40 extending from the respective end portions of the respective panels 2 as free continuations thereof. The panels 3 similarly fold inward along scored lines b to overlie the end flaps or laps 8 and 10 to lie substantially parallel to, and closely adjacent to, their respective cooperating panels 4, but are not pasted to the latter. The panels 1 and 2 fold upward at right-angles to the upper

45 face of the bottom C along score lines c. The end flaps or laps 8 and 10 fold inward at right-angles to the panels 2 along scored lines d to lie between panels 1 and 3, there being a free slight relative sliding movement between said flaps or laps 8 and 10 of each end of the respective pasted panels 2 and 4 incident to such folding due to 50 55

said flaps or laps 8 and 10 being free from each other whereby they may have relative movement for their full lengths to compensate for the two thicknesses of material and to avoid drawing, puckering or buckling. As thus disposed between said panels 1 and 3 the respective end laps 10 will extend across the respective openings 9' lengthwise of the panels 3 and will extend vertically of the panel 1 for width of 11'.

the lower faces of the respective laps 8 and accordingly said holes or openings 9' may extend up beyond the lower portions of the laps 8 or may not, this being rather immaterial so long as they are of such size and so positioned as to permit the passage of the tongues F through the respective panels 3 to operatively engage the lower edge faces of the respective laps 8.

faces of the respective panels 3 and will extend vertically

With expenses of \$1000,000,000, the cost of the new bridge will be \$100,000,000, or \$100 per foot.

5

held between the opposing faces of the end portions of the respective pairs of relatively movable panels and extending endwise across said openings, the inner laps having abrupt lower edge faces to be engaged by the cooperating upper free end locking faces of said cooperating tongues respectively extending through the respective openings and said inner laps being so firmly engaged by the outer laps as to prevent the lateral outward movement of the upper ends of the respective tongues beyond the respective lower edge faces of the respective inner laps.

5. 2. A paper board receptacle comprising a body having one end portion provided with resilient upwardly and outwardly presented locking tongues having abrupt free end locking faces, in combination with a bottom having an integral lip receiving said end portion and comprising a

lip portion, and inner corner lap, an outer corner lap, a pair of inner and outer panels, the inner panel being foldable inwardly and downwardly to lie substantially parallel to the outer panel, the inner panel being formed with an opening, and said laps folding at right-angles to said lip portion to lie parallel to each other with a relative sliding movement and lying behind said opening and between and being firmly frictionally gripped and held by the opposed faces of said panels, and the inner lap being formed with an abrupt lower edge face to be engaged by one of said locking tongues and being so firmly engaged by the outer lap as to prevent the lateral outward movement of the upper end of the cooperating locking tongue beyond the lower edge of said inner lap.
